UNITED STATES PATENT OFFICE.

FRANCIS L. COOK, OF SPRINGFIELD, MASSACHUSETTS, ASSIGNOR OF FIVE-EIGHTHS TO FRANCKE W. DICKINSON AND JOHN W. WILDER, OF SAME PLACE.

BOTTLE-STOPPER.

SPECIFICATION forming part of Letters Patent No. 651,183, dated June 5, 1900.

Application filed October 27, 1899. Serial No. 734,906. (No model.)

To all whom it may concern:

Be it known that I, FRANCIS L. COOK, a citizen of the United States of America, and a resident of Springfield, in the county of Hampden and State of Massachusetts, have invented certain new and useful Improvements in 5 Bottle-Stoppers, of which the following is a full, clear, and exact description.

This invention relates to improvements in 10 stoppers for bottles, the object being to provide a stopper composed of wood, and therefore very cheap and inexpensive, but so constructed as to have a sufficient flexibility to enable it to conform to the opening in the 15 neck of the bottle to fill the same while in compression or exerting a yielding force relatively thereto.

The stopper is more especially designed for 20 closing bottles having comparatively-large necks and mouths—such as those used for containing dentifrice and other powders, chemicals, or materials—so that by the removal of a supplemental stopper-cap the contents or portions thereof may be removed 25 from the bottle without the removal of the plug or stopper proper.

The invention consists in a stopper for a 30 bottle having the plug portion thereof formed annular with an intervening annular chamber and having the central member thereof constructed tubular and extended upwardly, the cap for closing the upwardly-extended end of said tubular part, and a portion for covering the top of the annular chamber with- 35 in the stopper-plug.

In the drawing, A represents the body or 40 plug portion of the stopper, having there- within the opening or chamber a.

The plug portion A of the stopper is formed 45 with a central opening, surrounding which is the annular upstanding portion k, which is preferably projected above the top of the plug portion, this upwardly-extended part being surrounded by the centrally circularly

apertured stopper top m, which is fitted about 45 the part k and has a concentric shoulder portion m², fitting between the external and internal walls of the said plug portion, between which external and internal portions is the annular space a, which imparts the resiliency 50 or flexibility to the stopper-plug. The web b unites the outer annular wall to the inner tubular part k. The cap n is removably fitted on the upwardly-protruding central tubular part k. 55

The said stopper is advantageous for employment in bottles having comparatively-large neck-openings and such as are employed for containing powders or pulverized or granulated material, such as dentifrice. 60 The parts n and m may be integrally formed, if desired, and the shoulder portion may be so constructed that in entering the downwardly-convergent annular space which is upwardly opening within the plug portion of 65 the stopper it will exert a crowding action to expand the outer wall, and thereby render it tighter in its fit within the bottle-neck.

The stopper may be made by turning from 70 solid wood or by reducing the wood to a pulp and producing the stopper by molding.

Having thus described my invention, what I claim, and desire to secure by Letters Patent, is—

A stopper for a bottle having the plug portion thereof formed annular with an intervening annular chamber, and having the central member thereof constructed tubular and extended upwardly, the cap for closing the upwardly-extended end of said tubular part, 80 and a portion for covering the top of the annular chamber within the stopper-plug. 75

Signed by me at Springfield, Massachusetts, this 25th day of October, 1899.

FRANCIS L. COOK.
